UNITED STATES PATENT OFFICE

2,165,636

ELECTRIC FUSE

George N. Lemmon, Homewood, Ala., assignor
to Southern States Equipment Corporation,
Birmingham, Ala., a corporation of Alabama

Application December 3, 1935, Serial No. 52,719

11 Claims. (Cl. 200—117)

This invention relates to circuit breakers of the 5
expulsion tube type. More particularly it relates
to spring means for ejecting or pulling out con-
ductors from the tube upon the occurrence of an
overload. The use of springs for removing the
flexible or fusible conductors from their ex-
pulsion tubes has heretofore been known, but
the spring and the associated parts have been
complicated in their cooperation and assembly
10 and this has made installation of a new conductor
within a used tube, in the field, a difficult opera-
tion and in some cases it has been necessary to
return the tube to the factory for insertion of a
new conductor. Other springs have had the dis-
15 advantage of occupying too much space or of
being situated in an inconvenient location.

This application is a continuation in part of
my copending application Serial No. 697,865,
filed November 13, 1933, now Patent No. 2,090,609,
20 issued August 17, 1937.

It is an object of my invention to provide an
improved spring for removing a flexible conductor
from an expulsion tube of a circuit breaker.

Another object of my invention is to provide
25 an improved spring for a circuit breaker of the
above type, which has means to guide the flexible
conductor as it passes through the end of the
tube and means to fasten the flexible conductor to
the spring.

30 Another object of my invention is to provide
a spring of the above type which has means for
guiding and centering the flexible conductor and
for securing it to the spring.

Other objects and advantages of my invention
35 will become apparent as it is described in con-
nection with the accompanying drawing.

In the drawing—

Figure 1 is a side elevation view of an expul-
sion tube type circuit breaker with a spring
40 formed according to the principles of my inven-
tion.

Figure 2 is a perspective view of a spring formed
according to the principles of my invention.

Figure 3 is a view of one end of an expulsion
45 tube showing my spring in operative position
connected to the fusible conductor.

Figure 4 is a view similar to Figure 3 but
with the spring seated in the recess of the tube
terminal.

50 Referring to the drawing a pair of conventional
pin type insulators 24 and 25 are mounted upon a
suitable support in spaced relation and have
mounted upon them terminals for securing an ex-
pulsion tube 21 of insulating material in position.
55 The tube is provided with conventional terminals

21a and 21b at its upper and lower ends. The
upper terminal being axially recessed and the re-
cesses being provided with internal screw threads
for the reception of a screw plug 22 which presses
down upon the enlarged head 16 of a flexible or
5 fusible conductor 15 which passes through the
tube and has a flexible end extending through
the terminal 21b at the lower end of the tube.
Conductor 16 may be of the type which has a
short portion more quickly fusible than the rest. 10

In order to place the conductor 15 under ten-
sion so that any unfused portions of it will be
pulled out of the tube upon the occurrence of an
overload I provide a helical coil spring 26 of di-
ameter slightly less than that of the tube terminal 15
21b. The inner end of this spring is bent to lie
diametrically across the spring axis and is pro-
vided with a loop 28 coaxial with the spring axis.
This loop is of diameter slightly larger than that
of the flexible conductor so that the conductor 20
may pass therethrough and be centered and guided
by the loop. This inner end of the spring
presses against the end of the tube terminal 21b.
The outer end of the spring 27 is coiled into a
small helical coil whose convolutions are in close 25
proximity and whose diameter is slightly larger
than that of the flexible conductor in order that
the conductor may be passed through the loop.
The extreme end 27' of the spring 26 is permitted
to extend beyond the circumference of the small 30
coil 27 in order that the flexible conductors 15
may be guided by it as the flexible conductor is
forced between adjacent convolutions of the
small coil and held there frictionally. Preferably
the spring 26 will be compressed before the flexi- 35
ble conductor is fastened to the small coil 27 so
that tension is applied to the conductor 15. The
extreme end of the conductor 15 is or may be
secured to the terminal 21b in any suitable
fashion such as by a screw 23. 40

I have found that the means I have provided
for securing the flexible conductor to the spring
and for guiding the flexible conductor in its
passage axially through the spring is very ef-
fective in preventing the spring from twisting it-
self sideways into an unworkable position. It 45
will be observed that the guiding and securing
means are part of the spring itself thus avoiding
the necessity of using additional parts to per-
form the essential functions of guiding and
fastening. 50

In Figure 4 I have shown a terminal 121 which
has a coaxial bore in its end for the reception of
the spring 26. Thus it is apparent that my in-
vention is capable of use with expulsion tubes 55

whose terminals have flat ends, or with tubes the ends of whose terminals have been bored out or formed with a recess. It will be observed however, that in the latter kind, need of the guide 5 loop at the inner end of the spring is no longer imperative since the walls of the recess will guide the spring against twisting into an unworkable position.

Modifications within the scope of my invention 10 will occur to those skilled in the art and therefore I do not limit myself to the exact form of the invention as illustrated.

I claim:

1. In an expulsion tube type of circuit breaker 15 having a flexible conductor extending through one end of the tube and adapted to be pulled through said end upon the occurrence of an overload, a helical compression spring pressing against said end of the tube and tending to pull said conductor out of said end, said spring having its outer end coiled into a small helical coil which is coaxial with the spring axis and has its convolutions in close proximity to one another whereby said flexible conductor may be fastened 20 to said spring by passing between and by being held by adjacent convolutions of said small coil, said spring having its inner end extending diametrically across the axis of the spring and having a loop through which said conductor passes and is guided, said loops being coaxial with the spring axis.

2. In an expulsion tube type of circuit breaker 25 having a flexible conductor extending through one end of the tube and adapted to be pulled through said end upon the occurrence of an overload, a helical compression spring pressing against said end of the tube and tending to pull said conductor out of said end, means formed on one end of said spring to guide the flexible conductor axially as it passes through said spring, means formed on the other end of said spring for securing said conductor to said spring in the 30 spring axis.

3. In an expulsion tube type of circuit breaker, 35 having a flexible conductor extending through one end of the tube and adapted to be pulled through said end upon the occurrence of an overload, a helical compression spring pressing against said end of the tube and tending to pull said conductor out of said end, means formed on opposite ends of said spring to position said conductor axially as it passes through said spring and to facilitate attachment of said conductor to 40 said spring.

4. In an expulsion tube type of circuit breaker 45 having a flexible conductor extending through one end of the tube and adapted to be pulled through said end upon the occurrence of an overload, a helical compression spring pressing against said end of the tube and tending to pull said conductor out of said end, means formed on one end of said spring for attaching said conductor to said spring in the spring axis by mere manual manipulation, and means for maintaining 50 the axial position of said conductor with relation to said spring.

5. In an expulsion tube type of circuit breaker, 5 having a flexible conductor extending through one end of the tube, and adapted to be pulled through said end upon the occurrence of an overload, a helical compression spring pressing against said end of the tube and tending to pull said conductor out of said end, and means on said spring for attaching said conductor thereto and for guiding said conductor axially through said spring.

6. In combination, an electrical fuse link, a tubular insulating housing for said link, and a coil spring member attachable at will by mere manual manipulation to a portion of the link external to said housing.

7. In combination, a tubular fuse housing of insulating material, a fuse link partly within and partly without said housing, and an independent spring member tensioning said link and held against said housing by said link, said spring 20 member having a guide at one end and holding means for the link at the other end.

8. In combination, a flexible electrical fuse link, a tubular insulation housing for said link for creating an expulsion effect on the arc as said 25 conductor ruptures, a helical spring coaxial with the flexible conductor and attachable at will to a mid-portion of the conductor by mere manual manipulation and tensioning the portion of the conductor within the housing but leaving unten- 30 sioned a portion of the conductor exterior of the tube.

9. In combination, a flexible electrical fuse link, a tubular insulation housing for said link for creating an expulsion effect on the arc as said 35 conductor ruptures, terminal members adjacent the ends of the housing, a helical spring coaxial with the flexible conductor and attachable at will to a mid-portion of the conductor by mere manual manipulation and tensioning the portion of the conductor within the housing but leaving un- 40 tensioned a portion of the conductor exterior of the tube, and means to secure the untensioned end to one terminal member outside the tube.

10. In combination, an expulsion tube fuse 45 housing of insulating material, a fuse link partly within and partly without said housing, an independent coil spring member held against the end of said housing by said link and attachable at will to a mid-portion of said link by mere manual 50 manipulation for tensioning the interior portion of the link and leaving the exterior portion of the link untensioned.

11. In an air break circuit breaker, an insulating tube having a terminal at one end, a conductor connected to said terminal and extending through said tube and having a flexible portion extending out the other tube end, a coiled spring coaxial with said tube and conductor and pressing against said other end of said tube and tensioning said conductor, said conductor passing axially through said spring and having a loose end freely attachable to a terminal bushing, and means for attaching said flexible portion to said 60 spring.

GEORGE N. LEMMON.
